SHORT RAILS FOR HOLLYWOOD BEDS

John Henry De Boer, Syracuse, N. Y.; Marine Midland Trust Company of Central New York and Benjamin E. Shove, executors of said John Henry De Boer, assigns to De Boer Manufacturing Company, Inc., Syracuse, N. Y., a corporation of New York

Application December 9, 1952, Serial No. 324,895

3 Claims. (Cl. 5—287)

My invention relates to short rails for display bedsteads; and is an improvement on the construction set forth in my expired Patent No. 991,049, dated May 2, 1911.

As set forth in that patent, the invention relates to that class of bedstead side rails which are made short in length for the purpose of temporarily locking the foot-board and head-board comparatively close together in their natural upright positions, for use in the show rooms of stores; and the object of the invention is to provide a very simple and effective device for use with the head-boards of Hollywood beds; or any other beds not having foot-boards of their own.

The device includes a rectangular frame formed of a good quality of wood with its corner portions in rigid interlocking engagement, and with the grain of the wood in each individual side of the rectangle running in the direction of the longitudinal extent of that individual side, said rectangular frame being preferably longer in one direction than the other.

This rectangular frame forms the short rail of my recent arrangement, and has the following advantage. It may be formed of material which is light in weight, is easily worked, and very cheap in price.

In the drawings, Fig. 1 is a diminutive perspective view of a device embodying the invention, showing one method of attaching it to the headboard of a Hollywood type bed. In this view the rectangular frame which forms the side rail of the device, is disposed its long way between the headboard of the bed and the footboard of the device.

Fig. 2 is a side elevation of the device as it appears when the rectangular frame which forms the side rail of the device is disposed its long way between the headboard and the footboard.

Fig. 3 is a vertical section of Fig. 2, looking in the direction of the arrow 3.

Fig. 4 is a vertical section of Fig. 2 looking in the direction of the arrow 4.

Fig. 5 is a sectional view of the device as it appears when the rectangular frame which forms the side rail of the device is disposed its short way between the headboard and footboard.

Fig. 6 is a top plan view of Fig. 2.

Fig. 7 is a bottom plan view of Fig. 2; and

Fig. 8 is a top plan view of Fig. 5.

In my original patent referred to hereinabove, the rectangular frames which formed the side rails of the device were provided with projecting hooks which engaged with pins anchored in the head and footboards of the bed; and were connected at their inner ends with a turn-buckle.

In my present arrangement I dispose of the turn-buckles entirely, and instead thereof provide a rectangular frame generally indicated by the letter A, longer in one direction than the other; and provided in its opposing shorter ends with longitudinal slots 3. Two bolts 4,

2

spaced somewhat apart from each other, pass through the headboard 1 of the bed at points in registration with the slot in the head end of the rectangular frame, with locknuts 6 on the inner projecting ends of said bolts, whereby the rectangular frame is rigidly attached to the headboard of the bed. The footboard 2 of the device is provided with a bore in registration with the slot 3 in the foot-end of the rectangular frame, and a bolt 8 passes inwardly through said footboard and said slot, with a wing-nut 10 on the inner end of said bolt, whereby the footboard of the device is rigidly secured in engagement with the foot-end of the rectangular side rail.

It will be observed that while the headboard is rigidly secured to one end of the rectangular frame by two bolts which will prevent the frame from lateral rocking on the headboard, the footboard is attached to the other end of the rectangular frame by only one bolt. However, in this connection, attention is called to the fact that the footboard has a shallow channel 7 in its inner side, into which channel the foot-end of the rectangular frame snugly fits, so that only one wing-nut is necessary to hold the footboard against any rotary movement on the outer ends of the rectangular frame, as clearly shown in Fig. 1 of the drawings. Hence the headboard and the footboard are held in rigid vertical engagement with each other.

In Fig. 5 of the drawings, the rectangular frame A is disposed its short way between the headboard and the footboard of the bed which arrangement gives a shorter bed rail than does the arrangement shown in Fig. 2. The bolts 4 with washers 5, are the same as those shown in Fig. 2; and the same is true of the bolt 8, the washer 9, and the wing-nut 10, also shown in Fig. 2. In this arrangement, however, the bolts 4 and 8 pass through bores in the two longer sides of the rectangular frame, as shown in Figs. 6 and 7. The position of these holes is also shown in dotted lines in Fig. 2.

When the rectangular frame is used its short way, as illustrated in Fig. 5, the slots 3 in the shorter sides of the rectangular frame are useless, but are not in the way.

In many Hollywood beds already on the market, the bolts in the headboards are at different heights above the floor, varying anywhere from 5" to 10", and it often happens that persons who have experienced inconvenience in making proper adjustments with the turnbuckle-arrangement desire to substitute the present arrangement therefor. This change is very easily made since the long slots 3 in the end sections of the rectangular frame make it possible to use the same bolts, washers, wing-nuts, etc., without changing any of them, the slots in the shorter ends of the rectangular frame being long enough to comprehend all the present positions of said parts. Thus, the rectangular frame A may be adjusted relative to the headboard 1 and footboard 2 to hold the headboard in upright position regardless of the position of the bolts 4 therethrough.

I claim:

1. A device for supporting the headboard of a bed in an upright position for display purposes comprising a substantially rectangular frame member, said frame member being secured at one end to said headboard by means providing vertical adjustability of the frame relative to the headboard, and a footboard secured to the opposite end of said frame member by means providing vertical adjustability of the footboard relative to the frame, whereby said device can be adjusted to position the bottom of said footboard in horizontal alignment with the bottom of said headboard to maintain the latter in upright position.

2. In a device for supporting the headboard of a bed in an upright position for display purposes, said headboard being provided with means to normally secure it

to the remainder of the bed, a substantially rectangular frame member, at least two opposed sides of said frame member having longitudinal slots therein, the slot in one of said frame member sides coacting with said headboard securing means to provide a vertically adjustable connection between the frame member and headboard, and a footboard secured to the opposite side of said frame member, said footboard having securing means coacting with the slot in said opposite frame side to provide a vertically adjustable connection between the footboard and the frame member, whereby said device can be adjusted to position the bottom of said footboard in horizontal alignment with the bottom of said headboard to hold the latter in upright position.

3. In a device for supporting the headboard of a Holly-
wood type bed and in an upright position for display purposes, said headboard being provided with fastening means to normally secure it to the remainder of the bed, a substantially flat, rectangular frame member, at least two opposed sides of said frame member having centrally disposed, longitudinal slots therein, the slot in one of said frame member sides coacting with said headboard fastening means to provide a vertically adjustable

connection therebetween, a footboard secured to the opposite side of said frame member, said footboard having a shallow longitudinal channel on the inner side thereof to slidably receive said opposite frame member side therein, and securing means in said footboard coacting with the slot in said opposite frame member side to provide a vertically adjustable connection between the footboard and frame member, said frame member being disposed in a substantially vertical plane between said head and footboards, whereby said device can be adjusted to position the bottom of said footboard in horizontal alignment with the bottom of said headboard to hold the latter in upright position.
